(57) CLAIM

The ornamental design for a sensory hideaway, as shown and described.

DESCRIPTION

FIG. 1 is a top, front, left perspective view of a first embodiment of a sensory hideaway showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a top, front, left perspective view of a second embodiment of a sensory hideaway showing our new design;

FIG. 8 is a front view thereof;

FIG. 9 is a rear view thereof;

FIG. 10 is a right side view thereof;

FIG. 11 is a left side view thereof; and,

FIG. 12 is a top view thereof.

The uneven-length broken lines define the bounds of the claimed design and form no part thereof. The oblique line shading in FIGS. 1 and 4-6 represents that the surfaces have a transparent, translucent, or reflective appearance. The even-length broken lines depicting the remainder of the sensory hideaway form no part of the claimed design.
